UNITED STATES PATENT OFFICE.

CHARLES F. PORTER, OF BROCKTON, MASSACHUSETTS.

DEVICE FOR DISPLAYING BOOTS OR SHOES.

SPECIFICATION forming part of Letters Patent No. 498,694, dated May 30, 1893.

Application filed December 5, 1892. Serial No. 454,093. (No model.)

To all whom it may concern:

Be it known that I, CHARLES F. PORTER, a citizen of the United States, and a resident of Brockton, in the county of Plymouth and State of Massachusetts, have invented certain new and useful Improvements in Devices for Displaying Boots or Shoes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a shoe which is provided with my device for displaying it to advantage. Fig. 2 is a longitudinal sectional view of the same. Fig. 3 is a perspective view of the displaying device, as it would appear if removed from the shoe and inflated. Fig. 4 is a view of the device as it appears when collapsed, as when not in use, or when about to be placed in a boot or shoe; and Fig. 5 is a detail sectional view of the pneumatic valve.

Like letters of reference denote corresponding parts in all the figures.

My invention has for its object to display foot-wear of all kinds in a neat and attractive manner; that is to say, displaying the boot or shoe as if it were upon a human foot, for the purpose of showing off its fit and style to the best advantage.

To this end, my invention consists in a flexible and collapsible shaped air-tight bag, or form, adapted to be inserted, in its collapsed state, into a boot or shoe, and to then be inflated so as to fill out the interior of the boot or shoe in the same manner as if this were occupied by a human foot or shaped wooden form or last.

Referring to the drawings, the letter A designates the shoe, and B a bag of rubber or other air-tight fabric, which is shaped approximately like a human foot, having a toe-piece a, instep b, heel c, and sole-piece d. The bag is closed at e where the ankle would be; but is provided at this point with a pneumatic valve C, adapted to be connected with an air-pump. This valve consists of a short tube D

connected with the bag and provided with a small central bore E. At its outer end, this tube is screw-threaded to engage with a correspondingly threaded tube G, having a bore H. This tube G has an exteriorly screw-threaded top or extension, also bored through in alignment with the bore H so as to constitute a continuation thereof, but contracted at its upper end so as to form a small circular opening h, which may be closed by screwing down a removable threaded cap K, which fits over and upon the threaded neck or extension of tube G, as clearly illustrated in Fig. 5. Within the vertical bore H is placed a valve-plug I, the lower end of which is reduced, as shown at i, to enable it to enter loosely the small central bore E in tube D; said bore forming not only an inlet for the air through tubes G and D into the flexible bag, but also serving as a guide for the lower end of the valve-plug when this moves up or down within its bore or valve-chamber H, so as to seat it with its lower end (above the reduced stem i) upon the seat D' where the contracted bore E enters the enlarged bore H. The upper end of the valve-plug I is made tapering, or in the form of a truncated cone, to enable the air to pass freely in and around it through the top aperture h, when cap K has been removed, and to fit into aperture h when the valve is closed. It will be seen that this shaped bag, when collapsed, can easily be placed within a boot or shoe, and by then inflating it with air by blowing through valve C or connecting the valve to an air-pump (cap K having first been unscrewed and removed), it will fill, and, by assuming the size and proportions of a human foot, will fill up the interior of the boot or shoe within which it is placed, as shown in Fig. 2. After it has been inflated to its full capacity, the air-valve C automatically closes, by the pressure of the air confined in the elastic bag against the under side of the valve-plug I, which forces its upper tapering end up against and partially into the small aperture h so as to close the same, after which the air-pump is detached and the cap K applied, when the boot or shoe is ready for display in the window or show-case.

As the bag B is flexible and yielding, and

the air with which it is filled possesses a certain degree of elasticity, it will readily accommodate itself to varying sizes and shapes, so that one style and size of bag may be used 5 for several different sizes and shapes of footwear. When it is desired to withdraw the bag, the air-valve is simply opened and the air let out, when the bag will collapse so that it can easily be pulled out.

10 This device is inexpensive, as well as simple and easy in its application, as it can be applied and again withdrawn in a moment of time.

Another advantage is its lightness (as contrasted with wooden lasts or shaping forms), 15 which permits of its being used with shoes displayed on the thin glass shelves of showcases without danger of breaking them. Again, these collapsed forms, which are light 20 in weight and take up but little room when not inflated, can be carried conveniently in the trunks of traveling salesmen and drum-

mers, and used by them in displaying their samples to the best advantage.

Having thus described my invention, I 25 claim and desire to secure by Letters Patent of the United States—

As an improved article, a flexible air-tight bag approximating in shape and size that of a human foot, adapted to be inserted into a 30 boot or shoe, and provided with a short tube connected therewith having a small central bore, the tube connected therewith provided with a removable cap, and the vertically reciprocating cap or plug located in said tubes, 35 substantially as described.

In testimony that I claim the foregoing as my own I have hereunto affixed my signature in presence of two witnesses.

CHARLES F. PORTER.
